UNITED STATES PATENT OFFICE.

MARTIN L. SCIVALLEY, OF DECHERD, TENNESSEE.

CHURN AND DOMESTIC MOTOR.

SPECIFICATION forming part of Letters Patent No. 269,964, dated January 2, 1883.

Application filed August 8, 1882. (No model.)

To all whom it may concern:

Be it known that I, MARTIN L. SCIVALLEY, of Decherd, in the county of Franklin and State of Tennessee, have invented certain new and useful Improvements in Churns and Domestic Motors; and I do hereby declare that the following is a full, clear, and exact description of the invention, which will enable others skilled in the art to which it appertains to make and use the same, reference being had to the accompanying drawings, which form a part of this specification.

Figure 1 is a top view. Fig. 2 is a side view. Fig. 3 is a longitudinal vertical sectional view, and Fig. 4 is an end view.

Corresponding parts in the several figures are denoted by like letters of reference.

This invention relates to domestic motors for operating beef-chippers, churns, egg-beaters, coffee-mills, and other domestic utensils; and it consists in certain improvements in the construction of the same, which will be hereinafter fully described, and particularly pointed out in the claim.

In the drawings hereto annexed, A represents a suitable frame, one side of which, B, is provided with laterally-projecting brackets C, connected by a longitudinal beam, D.

E is the main shaft, which is journaled in suitable boxes or bearings in the beams B D, and provided with a large driving-gear, F, and with an operating-crank, G.

H I are shafts mounted transversely in the frame A and beam D, which latter is provided with slots J to receive the outer ends of the said shafts, which are thus capable of being moved a short distance longitudinally in the frame. The side piece, B, of the latter is provided with two dovetailed recesses, K, in which are placed correspondingly-shaped blocks L, which may slide a short distance longitudinally in the recesses. The shafts H I are journaled in the blocks L L, and the latter are connected by a slide, M, resting upon the frame-piece B. The shafts H I are provided with

pinions N O, mounted upon said shafts between the frame-pieces B and D. It will thus be seen that by moving the slide M longitudinally either one of the said pinions may be thrown into engagement with the driving-gear, 50 while at the same time the other pinion is disengaged from said gear.

P P are locking-latches pivoted upon the frame-piece B, and adapted to bear against the ends of the slide M, thus serving, in connection with the dovetailed blocks L, to hold the said slide securely in any position to which it may be adjusted.

The frame A has a suitable bracket, Q, in which may be mounted the vertical stem or 60 shaft R of a churn-dasher or egg-beater, having at its upper end a pinion, S, engaging a bevel-gear, T, upon the shaft H, by which said device may be driven. The shaft I carries a beef-slicer, U, and may also be employed to 65 drive a coffee-mill, V, spice-mill W, and any other domestic utensil to which the power may be applied.

A treadle may be employed to drive the machine, when desired, instead of the crank.

I claim and desire to secure by Letters Patent of the United States—

The combination of the frame A, having beam B, provided with dovetailed recesses K and brackets C, connected by beam D, the main shaft E, having driving-gear F, the dovetailed blocks L, sliding in recesses K and connected by slide M, the shafts H I, mounted transversely in the frame, journaled in blocks L, and having pinions N O, and the latches P for locking the slide M in any position to which it may be adjusted, all as and for the purpose set forth.

In testimony that I claim the foregoing as my own I have hereto affixed my signature in 85 presence of two witnesses.

MARTIN L. SCIVALLEY.
